UNITED STATES PATENT OFFICE.

WILLIAM E. WHITE, OF CHICAGO, ILLINOIS.

BAR SPACER.

Application filed November 7, 1923. Serial No. 673,275.

To all whom it may concern:

Be it known that I, WILLIAM E. WHITE, a citizen of the United States, and resident of Chicago, in the county of Cook and State 5 of Illinois, have invented certain new and useful Improvements in a Bar Spacer, of which the following is a specification.

My invention relates to spacing devices for concrete work and particularly to an 10 extremely simple form adapted for economical machine production.

In accordance with the tendency toward simplification of the requisites in the art, efforts have been made to reduce the cost 15 of producing the accessories to concrete reinforcements and to that end a construction is here presented which is apparently the ultimate in the development along the lines suggested. The device consists essentially 20 of a single length of wire, looped at relatively close intervals, alternate laterally-extending loops being relatively angularly disposed. The resulting structure, when formed of stiff wire, is stable under all loads 25 and will sustain such loads without deflection either vertically or laterally.

A particular object in the design has been to provide a construction which might be produced in an automatic wire machine and 30 the complete article is delivered in two operations. The first operation is that of looping the wire and the second that of oppositely rotating alternate loops.

The invention will be more readily understood by reference to the accompanying drawing, wherein,

Fig. 1 is a side elevation of a spacer constructed in accordance with my invention;

Fig. 2 is a side view thereof, and,

Fig. 3 is an end view.

In manufacturing the article a single length of wire is used and by a suitable automatic machine the wire is bent to provide relatively closely spaced loops. The loops 45 consist of a base portion 10, which may be slightly upwardly curved between its ends and legs 11, which converge upwardly to their junction with straight aligned, intervening or connecting portions 12. The legs 50 converge to a point where they are, in effect, in contact although a slight degree of separation is unimportant.

After the loops are formed as described

and are in alignment, a second operation 55 serves to angularly dispose alternate loops in such manner that the loops occupy planes which intersect at the center line of the intervening portions. Due to the peculiar configuration of the parts which form the legs, the tendency toward collapsing is offset. The only effect of an excessive vertical load is to tend to bring the upper ends of the legs into abutting engagement.

The effective depth of the spacer is readily controlled by adjusting the machine to form 65 legs of greater length and obviously this result is secured by a change in only one of the elements of the device.

The construction herein described is distinguished from a construction in which alternate U-shaped portions of a continuous wire are laterally deflected to constitute legs in that the leg portions are rebent in the present structure thereby adding materially 70 to the strength thereof and to the ability to 75 resist vertical loads. A vertical load imposed on a structure of this application tends only to bring the abutting ends closer together, whereas a similar load applied 80 to a prior structure such as described would tend to separate and destroy the integrity 85 of the structure. The shaping of the loops is, of course, unimportant and while I have shown the deflected portions as of generally triangular outline, it will be understood that 90 this is wholly a matter of choice so long as the legs are rebent to bring the straight aligned portions substantially into contact.

One of the obvious advantages in the use 95 of a construction such as herein described is that of the easy handling, there being no sharp points or edges projecting and no tangling or interlocking of nested sections. The structure is capable of some modifications and I do not wish to be limited except as indicated in the appended claims.

I claim:

1. A spacer consisting of a length of stiff wire having substantially closed loops therein, said loops being separated by straight aligned intervening portions, said loops being alternately angularly disposed to occupy planes which intersect at the center line 100 of said intervening portions the ends of adjacent intervening portions being in contacting relation.

2. A bar spacer consisting of a single length of wire having loops formed therein, the loops being separated by straight aligned intervening portions, said loops being generally of triangular outline and comprising a base portion and legs which converge from the base toward their junction with the aligned connecting portions, alternate loops being angularly disposed to occupy planes which intersect substantially at the longitudinal center line of the intervening portions the ends of adjacent intervening portions being in contacting relation. ¹⁰
- 5 Signed at Chicago, Ill., this 29th day of October, 1923.

WILLIAM E. WHITE.
